UNITED STATES PATENT OFFICE.

FRANK B. RHOADS, OF PHILADELPHIA, PENNSYLVANIA, ASSIGNOR, BY MESNE ASSIGNMENTS, TO EDDY L. CLARK, OF BROOKLYN, NEW YORK, AND LYMAN D. HOWARD, OF PHILADELPHIA, PENNSYLVANIA.

CAR FOR ELEVATORS.

SPECIFICATION forming part of Letters Patent No. 425,828, dated April 15, 1890.

Application filed January 7, 1890. Serial No. 336,160. (No model.)

To all whom it may concern:

Be it known that I, FRANK B. RHOADS, a citizen of the United States, residing in the city and county of Philadelphia, State of Pennsylvania, have invented a new and useful Improvement in Cars for Elevators, &c., which improvement is fully set forth in the following specification and accompanying drawings.

10 My invention consists of the body of a car having means whereby it may be adjusted over a bin, chute, or other place of storage of material to accommodate the car to said place for loading and unloading purposes.

15 Figure 1 represents a top plan view of the running-gear and supporting-bolsters in full lines and body of a car in dotted lines embodying my invention. Fig. 2 represents an end elevation of the bolsters and a portion of 20 the rear truck. Fig. 3 represents a sectional view of the same. Fig. 4 represents a rear elevation of the rear truck, partially in section.

Similar letters of reference indicate corresponding parts in the several figures.

Referring to the drawings, A designates the main bolster of the rear truck of a car, to which is secured one section of a turn-table or fifth-wheel B and carrying friction-rollers C. Over said bolster A is mounted a beam D, having the other section of said turn-table or fifth-wheel B attached thereto and resting on the rollers C. To said beam D are connected bosses E, in which is mounted a rod F, having end collars G on each side of the bosses E to prevent the same from having an endwise movement, the said rod being also formed with a screw-threaded surface F' at or about the central portion thereof. One end H of 35 said rod F is constructed in the form of a bearing to receive a crank or handle J. (Shown in dotted lines, Fig. 1.) To the sides of said beam D are secured metal plates K to form bearings for a series of rollers L, mounted in the upper part of said beam. A cross-beam M is attached to the bottom of the car-sills N and having a screw-threaded collar P, connected to the upper central portion of the edge thereof, through which passes the screw- 45 threaded portion F' of the rod F. The beam 50

N rests on the rollers L and rides thereover in its lateral movement. The opposite end of the car-body is pivoted to the forward truck Q, as at R.

To move the car-body either to one side or 55 the other, the crank or handle J is turned to revolve the rod F, and the screw-threaded surface F' thereof coacts with the collar P on the beam N to cause the said body to move over the rollers L in the beam D. When the 60 rod F reaches a point at which it is about to bind with a collar P, it is relieved by the beam D, which turns on the turn-table or fifth-wheel B, and thereby the said rod F and collar P are always held in a proper relative position to each other.

This form of car is especially adapted for use in loading and unloading yards or other like places where it may be necessary to position a car for use with other mechanism— 70 such as elevating buckets, chutes, or analogous devices moving through a hatchway, hole, or opening for said purpose or attached to the car; but it will be understood that I do not confine myself to any specified usage, the 75 main object being to move one end of the car-body to such a position as to bring the same over the hatchway, opening, or hole of a bin or place of storage for the purposes set forth.

Having thus described my invention, what I 80 claim as new, and desire to secure by Letters Patent, is—

1. A car-body pivoted at one end and having means at the opposite end for laterally adjusting one end of the same to bring said 85 body outward over the frame in a horizontal position, substantially as described.

2. A car-body pivoted at one end and at its opposite end mounted on a bolster having rollers thereon, a screw-threaded rod attached 90 to said bolster, and a screw-threaded collar attached to said car-body, substantially as described.

3. A car-body pivoted at one end and at its opposite end mounted on a bolster and capable of being turned, a screw-collar connected to said car-body, and a screw-rod attached to the said bolster, substantially as described.

4. The collar P on the car-body, and the 100

beam D, having the screw-rod engaging with said collar P, and the bolster A of the truck, with the turn-table B between the same and said beam D, substantially as described.

5. A laterally-movable car-body pivoted at one end and having a threaded collar P on the opposite end, and a bolster rotatably mounted on a truck and carrying a screw-rod which en-

gages with said collar, whereby said body is laterally adjustable, and said bolster with its screw-rod conforms to the motion of said collar, substantially as described.

FRANK B. RHOADS.
